VERNIER SURFACE THERMOMETER
OR THE LIKE

George A. Argabrite, Malibu, Calif.
(2301 Federal Ave., Los Angeles, Calif. 90064)

Filed May 3, 1965, Ser. No. 85,069

Term of patent 14 years

(Cl. D52—7)

FIG. 1.

FIG. 2.

FIG. 3.

FIG. 4.

FIG. 1 is a perspective view of a vernier surface thermometer showing my new design;

FIG. 2 is a top plan view thereof;

FIG. 3 is a side elevational view thereof; and

FIG. 4 is a bottom view thereof.

I claim:

The ornamental design for a vernier surface thermometer or the like, substantially as shown.
